UNITED STATES PATENT OFFICE.

ROBERT D. BAKER, OF DETROIT, MICHIGAN.

PAVING APPARATUS.

1,388,690.

Specification of Letters Patent. Patented Aug. 23, 1921.

Application filed August 11, 1915. Serial No. 44,916.

To all whom it may concern:

Be it known that I, ROBERT D. BAKER, a citizen of the United States of America, residing at Detroit, in the county of Wayne 5 and State of Michigan, have invented certain new and useful Improvements in Paving Apparatus, of which the following is a specification, reference being had therein to the accompanying drawings.

10 The invention relates to paving apparatus, and has among the objects thereof to provide a paving apparatus which will crown and surface the paving material; to provide such a paving apparatus that will 15 produce a great degree of density of the paving material at the surface of the pavement; to provide a paving apparatus that will level the paving material and finish the same; to provide a paving apparatus which 20 will not only surface the paving material and crown the latter, but will also effect a finishing of the paving material; to provide a paving apparatus in which the control for all of the mechanism for propelling the apparatus and actuating the surfacing mechanism, is arranged at one side of the apparatus; to provide a paving apparatus in which the mechanism for propelling the apparatus may be so controlled as to regulate 25 the propelling of one side of the apparatus independently of the propelling of the other side; to provide a paving apparatus in which the surfacing section is so constructed as to allow the surface thereof in 30 engagement with the pavement material to be readily cleaned; to provide a paving apparatus in which the surfacing section may be adjusted to any predetermined crown; further, to provide a paving apparatus 35 which is comparatively simple in construction and will efficiently finish the pavement. Other objects of the invention will more fully hereinafter appear.

The invention resides in the peculiar construction, arrangement and combination of various parts as hereinafter set forth.

In the drawings:—

- Figure 1 is a perspective view of an apparatus embodying the invention;
- 50 Fig. 2 is a plan view thereof;
- Fig. 3 is a sectional view showing the paving section in its raised position;
- Fig. 4 is a view similar to Fig. 3 showing the surfacing section in its operative 55 position;
- Fig. 5 illustrates a detail of construction;

Figs. 6, 7 and 8 are sections on the lines *x-x*, *y-y* and *z-z* of Fig. 2 respectively;

Fig. 9 is a somewhat diagrammatic side elevation;

Fig. 10 is a cross-section showing the relation of the leveling device, the surfacing section, and the float;

Figs. 11 and 12 are perspective views illustrating certain details of construction;

Figs. 13, 14, 15, 16 and 17 illustrate certain details of construction;

Fig. 18 is a plan view showing a modified construction of finishing member; and

Figs. 19 and 20 illustrate modifications of 70 the mounting for supporting the surfacing section.

Fig. 21 is a sectional detailed view illustrating the cam connection for the wheels of the main frame; and Fig. 22 is a detailed 75 view illustrating the clutch connection between the drums.

In the one embodiment of the invention shown in the drawings, the apparatus is composed of a frame 1 upon which is arranged a surfacing section 2. The frame 1 is formed of carriages 3 and 4 each having wheels 5 for traveling upon tracks or side forms 6 at opposite sides of the pavement. These carriages are shown as open-centered 80 and carry shafts upon which are journaled the wheels 5. Preferably the frames are formed of channel irons. The surfacing section 2 has a comparatively wide sheet metal member 7 of a length to extend between the tracks upon which the wheels 5 travel.

I have found it very desirable to provide means for giving the surfacing member 7 a vibratory movement. In the particular 95 structure illustrated this is accomplished by a rotating shaft 8 journaled in bearings 9 carried by arms 10 extending laterally from and secured to the member 7. 11 are a second series of arms connected to the member 7 and extending laterally therefrom, the outer ends 12 being arranged beneath and adjacent to the shaft 8. Upon the shaft 8 and positioned to contact with the ends 12 of the arms 11 are vibratory 100 members or knockers 13 herein shown as in the form of a star gear. These vibratory members during the rotation of the shaft are adapted to have the teeth thereof impinge against the ends 12, which will effect 110 a vibration of the member 7.

The machine is driven by a motor 14

carried by the frame 3 and this motor drives a shaft 15 through the medium of a worm gear 16. The shaft 15 is journaled in bearings 17 18 carried by the frame 3 5 and preferably arranged at one side thereof. 19 is a second worm drive which actuates a shaft 20 upon which are loosely mounted two drums 21 and 22. Each of these drums is provided with a clutch 23 which is adapt- 10 ed to couple the drum to the shaft 20 and each clutch has a lever 24 by which it may be operated. Extending from the drum 21 to an anchor 25 suitably secured at a dis- 15 tance in advance of the apparatus is a cable 26. The anchor 25 is herein shown as in the form of a stake driven into the ground. 27 is a second cable which extends from the drum 22 rearwardly around a pulley 28 and then across the frame to a second pul- 20 ley 29. From there this cable extends for- 25 wardly to a second anchor 30. By this ar- 30 rangement when the clutches are moved to couple the drums to the shaft 20, during the operation of the motor the machine will be slowly propelled forward. As will be noted the control mechanism for uncoupling the drums from the shaft 20 and also the motor, are arranged on one side frame and can be readily controlled by a single opera- 35 tor. The shaft 8 is preferably driven from the motor at rather a high rate of speed, and this is accomplished by providing an extension 31 on the motor shaft, which has thereon a gear 32 that drives a gear 33 40 through the medium of the drive chain 34. The gear 33 is loose upon the shaft 8 and is adapted to be coupled thereto by a clutch member 35 that is fixed to rotate with the shaft but is free to slide longitudi- 45 dinally thereon so as to move the clutch 36 of the member 35 into or out of engage- 50 ment with the clutch teeth 37 on the hub of the gear 33. 38 is a lever for shifting the clutch member 35, the lever being ful- 55 crumed at 39 to a bracket on the frame of the carriage 3.

Preferably there is arranged in advance of the surfacing section a striker bar for leveling the concrete or other pavement 50 material before it is acted upon by the surfacing member. Thus as shown, 40 is a bar having the under face thereof of a contour to conform substantially to the crown desired for the pavement. This bar is pro- 55 vided with slots or bearings 41 adjacent opposite ends which engage rollers 42 carried by arms 43. Pivotally connected to a bracket 44 in the bar 40 is an arm 45 which is pivotally connected to a crank 46 attached 60 to an extension 47 of the shaft. Thus during the rotation of the shaft 15 the arm 45 will be reciprocated back and forth, which will cause the reciprocation of the member 40 crosswise of the apparatus.

65 Mounted adjacent each end of the sheet

metal member 7 are brackets 47 which en- 70 gage a pair of spaced arms 48 and 49 car- 75 ried by the side frame. Four of the brack- 80 ets 47 are shown arranged at each end of the member 7, each of the arms being en- 85 gaged by a pair of brackets. The arm 48 at each side of the frame has the outer 90 end thereof journaled in bearings 50 on the side frame, while the outer ends of the arms 49 engage seats or bearings 51 on the top of the side frame, which seats are open at the top. The arm 49 is secured to the seat 51 by bolts having lateral extensions 52 adapted to be turned over the top of the arm to hold it to its seat. The arrange- 95 ment is such that the arms 48 and 49 will normally support the member 7 in horizontal position, but as the arms 49 may be raised out of the seats 51, and since the arms 48 are pivoted, the surfacing section may be turned about the arms 48 as pivots, to the position shown in Figs. 3 and 9, thereby permitting ready access to the bottom face of the member 7 for cleaning. When the member 7 is turned up the drive chain 34 90 will of course be removed from the sprocket 33. To permit of turning the section 2 up- 95 ward the side members of each frame are formed with inwardly-extending portions 53 so as to permit the ends of the member 7 to clear the inner sides of the frames when the surfacing section is turned about the members 48 as pivots.

It is desirable to have the surfacing section vertically adjusted in relation to the frame, and this is accomplished by having the inner ends of the arms 48 and 49 en- 100 gage vertically-adjustable bearings in the brackets 47. As shown each bracket 47 is provided with a plate 54 upon which is arranged an adjustable wedge-shaped mem- 105 ber 55 that carries the arm. 56 is a set screw for clamping the arm against the wedge-shaped member 55. To vary the height of the surfacing section it is merely 110 necessary to release the set-screw 55 and adjust the wedge to either raise or lower the arm and then tighten the set-screw.

The member 7 has a longitudinal contour 115 similar to the crown desired for the finished pavement, and in order to permit the surfacing section to be adapted for roads of different contours, the member 7 is so formed as to permit the longitudinal contour thereof to be adjusted to any desired form, within 120 certain limits. Thus 57 are a plurality of uprights secured to the member 7 adjacent one side edge thereof, the uprights being longitudinally spaced and diminishing in height in opposite directions from the center 125 uprights. 58 are threaded bolts pivotally connected as at 59 to the uprights, and 60 are turn-buckles engaging the threaded ends of the member 50. As shown, the uprights— except one at the extreme end of the series— 130

carries two of the pivoted bolts 58 which project therefrom in opposite directions. 61 is a second series of uprights and turn-buckles positioned adjacent the opposite side of the member 7, this series being of similar construction and arrangement to the series 57. Thus by adjusting the turn-buckles the longitudinal contour of the member 7 may be varied as desired, within, of course, certain limits.

The member 40 is adapted to be raised and lowered, and to this end the shafts 43 upon which the rollers 40 are mounted are in the form of cranks mounted on bearings 62. 63 is a lever secured to one crank and having portions projecting upon opposite sides of the crank. 64 are arms projecting upon opposite sides of the other crank, and 65 and 66 are cables cross connecting the lever and arms. Thus by adjusting the lever 63 the cranks will be actuated to raise or lower the rollers 40 and therefore the striker bar. 67 is a chain having one end secured to the lever 63 and having the other end adjustably engaging the hook 68 on the frame of the carriage 3. Journaled at the end of the carriages are rollers 69 which receive the thrust of the striker bar.

Secured to the bottom of the striker bar 30 is an angle plate 70, one flange 71 of which extends beneath the bar and the other flange 72 of which is provided with a plurality of slots 73 for securing bolts 74. As shown, the flange 72 is severed at intervals, as indicated at 75 and the slots are elongated so as to permit the angle plate to be adjusted to the desired longitudinal contour.

I also preferably provide in rear of the machine a finishing member, which will act 40 to finish the surface of the pavement in the manner which heretofore has been accomplished by the usual hand-floats. This finishing member 76 is herein shown as composed of a flat metallic member 77 having standards 78 and turn-buckles 79 of a construction similar to that shown and described in connection with the surfacing section, except that but one series of standards and turn-buckles are employed. This permits the longitudinal contour of the member 76 to be regulated to any predetermined crown. Preferably in order to stiffen the member 76 angle members 80 are secured at opposite edges thereof. This member is 55 attached to the rear of the machine by means of flexible connections or cables 81, so as to be free to rest upon the concrete. It acts in a manner similar to a hand-float.

As will be noted upon reference to Figs. 60 6, 7 and 8 the surfacing section has secured to the forward edge thereof a member 82. This member is preferably in the form of an angle strip having one flange 83 connected to an angle strip 84 attached to the surfacing plate 7, while the other flange 85

of the strip 82 is provided with a groove 86 extending longitudinally thereof and above the plane of the bottom of the surfacing plate 7, the purpose of which will more fully hereinafter appear.

In order to permit the machine to be raised so as to lift the surfacing member out of engagement with the paving material, the wheels of one of the frames, as the frame 4, are journaled upon eccentric bearings 87 and 75 these eccentric bearings may be turned through the medium of a hand-lever 88 and cranks 89 so as to raise the machine. If desired the wheels of the other frame may be similarly journaled.

Preferably each wheel of the frame has the traction face 90 thereof of a greater width than the track 6 upon which it travels. This permits a slight variation in the width of the machine, due to the change in the crown of the surfacing section. This slight change in the width of the machine does not affect the operation of the member 40 since the slots 41 thereof are of a sufficient length to permit the change to be made. Preferably the rear ends of the carriages are connected by means of a rod 91 having a turn-buckle 92 therein.

In operation of the apparatus, assuming that the finishing member, the surfacing section and the striker bar have been adjusted to the proper crown, the operator arranges in advance of the machine and upon opposite sides of the road, the anchors 25 and 30 and secures the free ends of the cables thereto. The levers are shifted to disengage the drums from the shaft 20 and the gear 33 is uncoupled from the shaft 8. The motor is then started, but with the clutches so arranged the apparatus will not be propelled, 95 nor will the shaft 8 be actuated. After the concrete has been placed in advance of the machine and roughly leveled by hand or in any other suitable manner, the clutches are operated to set the shaft 8 in motion and drive the drums. The machine will then be propelled slowly forward, while the knockers will effect a vibration of the paving section. As the machine is propelled forward the striker bar 40 levels and crowns the material, and when the surfacing section is brought into engagement with the paving material, it not only places considerable pressure thereupon, but also the vibration of the surfacing section, accomplishing a tamping of the material, has a tendency to bring to the top the finer particles of the cement or other paving material. The vibration which is produced preferably is rather rapid and the tamping effect is accomplished 110 while the pavement material is under pressure. This I find produces a denser and more desirable surface than can be accomplished by the usual hand method. It is 120 also very noticeable in the operation of the

130

machine upon concrete pavements, that a considerable degree of moisture is brought to the surface, which is very desirable since it prevents the surface from drying out too fast and producing what is known as surface cracking or checking.

- Where a particularly smooth face is desired for the pavement the finishing member 76 is employed, though the float may be dispensed with if desired. The effect of the float is to finish the pavement surface in the same manner as usually accomplished by the ordinary hand-floating operation, though there is not the necessity for the floating of the pavement surface after it is subjected to the operation of the surfacing section, as there is when the pavement material is leveled and crowned by the old striker bar method.
- 20 The pressure which is placed upon the concrete may be varied by raising or lowering the surfacing section through the medium of the adjustable wedges 55, and also by varying the relative heights of the striker bar and surfacing section.

The bearings 9 for the shaft 8 are vertically adjustable so as to permit the bearings to be properly aligned when the contour of the surfacing section is varied. Also by 30 raising or lowering these bearings the impact of the members 13 upon the outer ends of the arms 11 may be regulated, and thereby the vibration through which the surfacing section is subjected increased or decreased 35 as desired. As shown in Fig. 13, the bearings 9 are carried by brackets 93 adjustably engaging supports 94 on the member 7.

The uprights and adjustable connections therebetween on the member 7 form a very 40 rigid truss for this member, allowing the latter to be used as a bridge upon which the operator of the machine may stand. This is highly advantageous as it allows the operator to be in position to fill in low spots in the 45 concrete between the striker bar and the surfacing section. These low spots will only occur when if in leveling the concrete the road bed is not filled to a sufficient height with the concrete.

- 50 During the operation of the apparatus there is a tendency for concrete, stones or the like to get on to the tracks and cause the wheels to be raised out of engagement with the tracks. To prevent this I arrange in advance of each wheel a guard in the form of a plate 94 vertically adjustable, secured to bolts 95 rigidly attached to the carriage frame.

As before described, the surfacing section 60 has at its forward edge a comparatively thin outwardly-extending flange. This flange acts to remove large stones or the like from the surface of the concrete. Thus as the surfacing section moves forward the flange 65 will tend to pass under the large stones or

the like, which will collect upon the top of the flange and may be removed at will. I find that when this flange is provided with the longitudinally-extending groove the finer material will be brought to the surface. 70 Thus as soon as the surfacing section places pressure upon the concrete the finer material will be forced into the groove, and as the surfacing section travels along the finer material which is in a very plastic condition 75 will be spread over the top forming a top surface for the pavement of very fine concrete. If desired, the striker bar may also be provided with a laterally-extending flange similar to the flange on the forward edge of 80 the surfacing section.

In order to prevent the drums from unwinding when the machine is at rest dogs 96 are provided which have the forward ends arranged to engage apertures 97 in the 85 drums. The dogs, however, will allow free rotation of the drums to wind the cables thereupon when the machine is in use.

In Fig. 18 I have shown a modification of finishing member. This member comprises a bar 98 which may be of the same construction as the striker bar 40 except as herein shown is provided with a truss 99. The bar is journaled upon rollers 100 and is adapted to be reciprocated through the 95 medium of an extension 101 of the shaft 15, the connection between the bar 98 and the extension 101 being similar to the driving connection for the striker bar, while in Fig. 18 the shafts 102 which carry the member 98 100 are not shown as adapted to be rotated to raise or lower the rollers 101. It will of course be readily understood that connection for raising and lowering the member 98 may be employed for instance in connection similar to that shown for raising and lowering 105 the striker bar.

In Figs. 19 and 20 are illustrated a modification of the means for raising and lowering the surfacing section. Thus instead of 110 raising and lowering the frame by means of eccentrics associated with the wheels, the surfacing section is mounted to raise and lower in relation to the frame as shown. 103 is a bearing member within which is arranged a member 104 having an eccentrically arranged opening therein for receiving the end of the member 48. The member 49 is provided with a similar mounting, and connecting the eccentrics 104 is a link 106 which 115 is pivotally attached to the eccentrics at 107. 108 is a second link connected to a hand-operated lever 109. Thus, by adjusting the lever 109 the eccentrics may be actuated to raise or lower the members 48 and 49. The 120 member 49 is pivoted in its eccentric and by removing the bolt 105 which secures the links 106 and 108 to the eccentric for the shaft 48 the surfacing section may be moved 125 into its raised position, it being understood, 130

of course, that the connection at each side of the frame is the same.

My invention may be embodied in various specific constructions, and while I have shown and described a very desirable form of the apparatus, I consider the invention to be of sufficient scope to embrace various modifications.

What I claim as my invention is:—

1. In a paving apparatus, the combination of a frame, a surfacing section mounted on the frame, a rotary shaft, a knocker on the shaft, and a projection on the surfacing section in the path of the knocker, whereby a vibration of the surfacing section is effected.

2. In a paving apparatus, the combination of a frame, a surfacing section mounted on the frame, a rotary shaft, and a knocker on the rotary shaft adapted to impinge upon a portion of the surfacing section and produce a vibration of the surfacing section.

3. In a paving apparatus, the combination of a frame, a surfacing section mounted on the frame, a rotary shaft, and a series of knockers on said shaft adapted to impinge upon portions of the surfacing section and produce a vibration of the surfacing section.

4. In a paving apparatus, the combination of a frame, a surfacing section mounted on the frame, a rotary shaft extending longitudinally of the surfacing section, a plurality of spaced knockers on said shaft, said surfacing section having portions in the paths of said knockers whereby a vibration of the surfacing section is effected upon a rotation of said shaft.

5. In a paving apparatus, the combination of a frame, a surfacing section mounted on the frame, a plurality of bearings carried by the surfacing section, a shaft journaled in said bearings, a plurality of knockers on said shaft, and projections on the surfacing section extending into the paths of said knockers, for the purpose described.

6. In a paving apparatus, the combination of a frame, a surfacing section mounted on the frame, a rotary shaft, a knocker on said shaft adapted to impinge against a portion of said surfacing section, means mounted on said frame for propelling the latter, and a drive connection between said propelling means and said shaft.

7. In a paving apparatus, the combination of a frame, a surfacing section thereon composed of a surfacing member, and means for varying the longitudinal contour of said member, comprising a plurality of spaced uprights on said member and adjustable connections between said uprights.

8. In a paving apparatus, the combination of a frame, a surfacing section thereon composed of a surfacing member, and means for varying the longitudinal contour of said member, comprising a plurality of spaced uprights on said member and adjustable

connections between said uprights including turn-buckles.

9. In a paving apparatus, the combination of a frame, a surfacing section thereon composed of a surfacing member, and means for varying the longitudinal contour of said member, comprising a plurality of spaced uprights on said member, rods extending between said uprights, and turn-buckles connecting said rods.

10. In a paving apparatus, the combination of a frame, a surfacing section thereon composed of a surfacing member, and means for varying the longitudinal contour of said member, comprising a plurality of spaced uprights on said member, rods pivoted to the uprights, and turn-buckles connecting said rods.

11. In a paving apparatus, the combination of a frame, a surfacing section thereon composed of a surfacing member, and means for varying the longitudinal contour of said member, comprising a plurality of spaced uprights on said member varying in length from the center of said member toward its ends, and adjustable connections between said uprights.

12. In a paving apparatus, the combination of a frame, a surfacing section thereon composed of a surfacing member, and means for varying the longitudinal contour of said member, comprising a plurality of rows of spaced uprights on said member, and adjustable connections between adjacent uprights of the same row.

13. In a paving apparatus, the combination of a frame, a surfacing section, and a connection between said frame and said surfacing section permitting the latter to be adjusted to position to provide access to the bottom of the surfacing section for cleaning or the like.

14. In a paving apparatus, the combination of a frame, a surfacing section, and a pivotal connection between said frame and said surfacing section permitting the latter to be rocked to a position to provide access to the bottom of the surfacing section for cleaning or the like.

15. In a paving apparatus, the combination of a frame, a surfacing section, and a pivotal connection between said frame and said surfacing section permitting the latter to be rocked upwardly to expose the bottom thereof for cleaning or the like.

16. In a paving apparatus, the combination of a frame, a surfacing section, a pivotal connection between said frame and said surfacing section permitting the latter to be rocked upwardly to expose the bottom thereof for cleaning or the like, and means for securing said surfacing section in its operative position.

17. In a paving apparatus, the combination of a frame, a surfacing section, spaced

75

105

110

115

120

125

130

- arms upon each end of said section adapted to be supported from the frame, a bearing on the frame in which one of the arms at one end of said section is journaled, and a 5 second bearing in which the corresponding arm at the opposite side of the frame is journaled, each of the other arms having a detachable engagement with the frame, for the purpose described.
- 10 18. In a paving apparatus, the combination of a frame including spaced supporting members arranged at opposite sides of the frame, a comparatively wide surfacing section of a width to span a roadway extending between said supporting members, and a connection between said supporting members and said surfacing section permitting the latter to be rocked upwardly to expose the bottom of the surfacing section, 15 for the purpose described.
19. In a paving apparatus, the combination with the frame, of a paving section, arms for supporting the paving section from the frame, bearings on the paving section 25 with which said arms are engaged, and means for vertically adjusting the arms in said bearings, for the purpose described.
20. In a paving apparatus, the combination with the frame, wheels for supporting said frame arranged at opposite sides thereof, a surfacing section carried by the frame, and means for propelling the frame, comprising a pair of drums, cables leading from said drums and adapted to be anchored at 35 their outer ends, a shaft upon which said drums are mounted, and a clutch connection for operatively connecting one of said drums to and disconnecting it from the shaft, and means for driving said shaft.
- 40 21. In a paving apparatus, the combination with the frame, wheels for supporting said frame arranged at opposite sides thereof, a surfacing section carried by the frame, means for propelling the frame comprising 45 a pair of drums, cables leading from said drums and adapted to be anchored at their outer ends, a shaft upon which said drums are mounted, a clutch connection for operatively connecting one of said drums to and 50 disconnecting it from the shaft, independent clutch connections between the drums and the shaft, and means for driving said shaft.
22. In a paving apparatus, the combination with the frame, wheels for supporting 55
- said frame arranged at opposite sides thereof, a surfacing section carried by the frame, a pair of drums arranged at one side of the frame, a shaft upon which said drums are mounted, independent connections between 60 said shaft and said drums, means for driving said shaft, a cable on one drum leading forwardly to an anchor, a cable on the other drum leading to the other side of said frame and forwardly to an anchor, and a shive 65 on the last-mentioned side of the frame over which said last-mentioned cable passes.
23. In a paving apparatus, the combination with the frame, wheels for supporting said frame at opposite sides thereof, a surfacing section mounted on the frame, a motor on the frame arranged at one side thereof, a shaft on said frame arranged upon the same side as the motor, a drive connection between said shaft and said motor, drums 70 loosely sleeved upon said shaft, independent clutch connections between said drums and said shaft, means for controlling said clutch connections, and independent cables leading from said drums forwardly to anchors, for 75 the purpose described.
24. In a paving apparatus, the combination with a frame, a surfacing section mounted on the frame, means for varying the longitudinal contour of said surfacing section, 80 a rotary shaft, adjustable bearings for the rotary shaft carried by said surfacing section, and means on the shaft for effecting a vibration of the surfacing section.
25. In a paving apparatus, the combination of a frame, a surfacing section carried by the frame comprising a member adapted 85 to span a roadway and having a surfacing face on the under side thereof and a laterally extending flange at the forward edge 90 of said surfacing face provided with a longitudinally extending groove.
26. In a paving apparatus, the combination with spaced carriages, of a surfacing member extending therebetween, and a common means for varying the contour of said member and for trussing said member to 95 form a bridge thereof for an operator.
- In testimony whereof I affix my signature in presence of two witnesses.

ROBERT D. BAKER.
